UNITED STATES PATENT OFFICE.

OSVALD E. RASMUSSEN, OF WEST HOBOKEN, NEW JERSEY, ASSIGNOR TO WESTERN ELECTRIC COMPANY, INCORPORATED, OF NEW YORK, N. Y., A CORPORATION OF NEW YORK.

CALLING DEVICE.

1,293,545.

Specification of Letters Patent.

Patented Feb. 4, 1919.

Application filed July 24, 1917. Serial No. 182,489.

To all whom it may concern:

Be it known that I, OSVALD E. RASMUSSEN, a subject of the King of Denmark, residing at West Hoboken, in the county of 5 Hudson and State of New Jersey, have invented certain new and useful Improvements in Calling Devices, of which the following is a full, clear, concise, and exact description.

10 This invention relates to calling devices, and more particularly to calling devices for automatic and semi-automatic telephone systems.

An object of this invention is to provide 15 an improved arrangement, whereby the dial of the calling device cannot be operated a second time until the transmission of impulses resulting from a previous actuation of the dial has been completed.

20 Another object of this invention is the provision of improved means for hiding during the transmission of the impulses, the symbols normally visible through the finger holes of the dial.

25 In general, the calling device embodying the present invention consists of means for permitting the dial to rotate backward a small portion of its forward rotation, and means operated by this limited backward 30 rotation for releasing the impulse mechanism, and for locking the dial against further rotation in either direction during the operation of the impulse mechanism. The dial is locked in such a position that the 35 symbols normally seen through the finger holes of the dial are hidden by the portion of the dial between adjacent finger holes.

The drawing shows a perspective view of 40 the sender with its case removed so that the operating parts of the mechanism may be more clearly disclosed. The sender is provided with the shaft 10, rotatably mounted in the bottom of the case (not shown). A finger dial 11 is fastened to the upper end 45 of this shaft and has holes whereby it may be operated. Normally, these holes are directly above symbols on a stationary plate 12, which is fastened to the case in any suitable manner. This plate also serves as 50 the upper support of the shaft 10. The toothed wheel 1 is fastened to the lower end of the shaft 10.

One end of a coil spring 2 is fastened to

the wheel 1, and the other end is fastened to a pin 14 mounted upon an impulse wheel 55 6. This impulse wheel is loose on the shaft 10 and carries a plurality of upwardly projecting pins 15, which are arranged to engage the contact spring 16 during rotation of the wheel, and thereby open the contact 60 between springs 16 and 17. The wheel 6 is normally prevented from rotating by a dog 7 which is carried by a lever 8, pivoted in the bottom of the case by screw 30. The wheel 6 meshes with pinion 18 which may 65 be connected by means of the shaft 19 to any well-known type of governor to control the speed of rotation of said wheel. Between stationary plate 12 and the impulse wheel 6 a hub cam 4 is mounted upon the shaft 70 10. This cam is arranged to move longitudinally on the shaft, but rotates therewith. A spring 22 normally holds a cam portion 20 of the hub cam in a groove of a sleeve 21, which is fastened to the impulse 75 wheel 6. The hub cam has a flange 24 which engages one end of a bell crank lever 5, which is pivotally mounted on a projection 13 of the plate 12. The other end of the 80 lever 25 pivotally mounted on the lever 8. This lower end of the bell crank lever is also arranged to engage the projection 26 of the lever 8 and thereby rock the lever about its pivot 30. The other end of the 85 lever 25 controls a pawl 3 which is in operative relation to the toothed wheel 1. A spring 28 is fastened to the projection 29 of the lever 8 and to the case (not shown) in such a manner that its line of action may 90 be changed from one side of the pivot 30 to the other side by the movement of the lever 8 so as to hold the lever 8 in whatever position it is moved.

The operation of the device is as follows: 95 Movement of the dial 11 in a clockwise direction through an angle corresponding to the digit selected, moves the shaft 10 and the toothed wheel 1, and also places the spring 2 under tension. During this movement the dog 7 is in engagement with the impulse wheel 6 and thereby prevents the rotation thereof. The hub cam 20 also moves with the shaft 10 and slides up thereon, thereby 100 rocking the bell crank lever 5, which, in turn, rocks the lever 25 and moves the pawl 105

3 into engagement with the toothed wheel 1. During the forward movement of the wheel 1, however, the pawl 3 only rides over the teeth thereof. When the dial 11 is released 5 the toothed wheel 1 starts to rotate backward due to the tension of the spring 2, but as soon as a tooth of the wheel engages the pawl 3 it rocks the lever 8 about its pivot point 30. This movement of the lever 8 10 moves the projection 9 into engagement with the toothed wheel and prevents further rotation thereof. This movement of the lever 8 also removes the dog 7 out of engagement 15 with the impulse wheel 6, which is now free to move under the influence of the spring 2 and the governor (not shown) attached to the shaft 19. This slight backward movement of the dial 11, produced before the toothed wheel 1 is locked, is sufficient to 20 move the dial so that the portions thereof, which are between the finger holes, cover up the symbols on the stationary plate 12. In this way the symbols remain covered up until the toothed wheel 1 is released. When 25 the impulse wheel 6 has been rotated in a clockwise direction and has produced the predetermined number of impulses in the circuit through the contact springs 16 and 17, the groove of the sleeve 21 will be brought 30 back into engagement with the cam 20 of the hub cam 4. This groove of the sleeve 21 is so arranged that the cam 20 will drop down into it before the spring 2 has transmitted all the energy that was stored up in 35 it by the clockwise rotation of the dial. As soon as the cam 20 drops down into the groove the bell crank lever 5 is moved back into its normal position. This movement of the bell crank lever rocks the lever 8, which 40 moves the dog 7 into engagement with the impulse wheel 6, and thereby stops it from further rotation. It will, therefore, be seen that the impulse wheel 6 is stopped rotating before cam 20 has reached its normal position 45 in the groove of the sleeve 21. Since the movement of the lever 8 also removes dog 9 from engagement with the toothed wheel 1 and the return movement of the bell crank lever 5 moves the lever 25 so as to withdraw 50 pawl 3 from engagement with the wheel 1, this wheel 1 is free to rotate. The energy, which is still left in the coil spring 2, will, therefore, rotate this wheel 1 counter-clockwise the slight amount necessary for the cam 55 20 to assume its normal position. This slight rotation of the toothed wheel is sufficient, however, to move the dial so that the symbols are again visible through the finger holes. All parts of the sender are now in 60 their normal positions and the sender is in position for a subsequent operation.

What is claimed is:

1. In a calling device, a rotatable dial having finger holes, a stationary member 65 carrying symbols normally visible through

said finger holes, an impulse transmitting mechanism, means for operating said mechanism, and means for locking said dial in a position to hide said symbols during the operation of said impulse transmitting 70 mechanism.

2. In a calling device, a rotatable dial having finger holes, a stationary member carrying symbols normally visible through said finger holes, an impulse transmitting 75 mechanism, means for operating said mechanism, means for locking said dial in a position to hide said symbols during the operation of said impulse transmitting mechanism, and means operated at the end of the opera- 80 tion of said mechanism for releasing said dial and moving it into a position in which said symbols are visible through said finger holes.

3. In a calling device, a rotatable dial hav- 85 ing finger holes, a stationary member carrying symbols normally visible through said finger holes, an impulse wheel, means for rotating said impulse wheel in accordance with the forward rotation of said dial, 90 means for rotating said dial backward a small portion of its forward rotation, and means operated by said backward move- 95 ment for releasing said wheel and for locking said dial in a position to hide said symbols during the movement of the wheel.

4. In a calling device, a rotatable dial having finger holes, a stationary member carrying symbols normally visible through said finger holes, an impulse wheel, means for 100 rotating said impulse wheel in accordance with the forward rotation of said dial, means for rotating said dial backward a small portion of its forward rotation, means 105 operated by said backward movement for releasing said wheel and for locking said dial in a position to hide said symbols during the movement of the wheel, and means operated at the end of the operation of said wheel for moving said dial into a position 110 in which said symbols are visible through said finger holes.

5. In a calling device, a rotatable dial, an impulse wheel, means for rotating the impulse wheel in accordance with the forward 115 rotation of said dial, means for locking the wheel against rotation during the forward rotation of the dial, means for rotating said dial backward a small portion of its forward rotation when said dial is released, and 120 means operated by said backward rotation for releasing said impulse wheel and for locking said dial against rotation in either direction during the movement of said wheel.

6. In a calling device, a dial, an impulse 125 wheel, connecting means between the impulse wheel and the dial for rotating the wheel a distance each time in response to the forward rotation of the dial, means for locking the impulse wheel against rotation, and 130

means controlled by the dial for releasing the impulse wheel and for locking said dial against rotation in either direction during the movement of said wheel.

- 5 7. In a calling device, an impulse transmitting mechanism, a rotatable dial for operating said mechanism, means for permitting the dial to rotate backward only a portion of its forward rotation, and means operated by said backward rotation of the dial for causing the said mechanism to transmit impulses and for locking said dial against rotation in either direction during said operation of the mechanism.
- 10 8. In a calling device, a rotatable dial, an impulse wheel, means for rotating said wheel, means for normally locking said wheel against rotation, and means operated by a slightly backward rotation of said dial 20 after a forward rotation for releasing said impulse wheel and for locking said dial

against rotation in either direction during said movement of the wheel.

9. In a calling device, a rotatable dial having finger holes, a stationary member carrying symbols normally visible through said finger holes, an impulse wheel, means for normally locking said wheel against rotation, means for rotating said wheel in accordance with the forward rotation of said wheel, means for rotating said wheel backward a small portion of its forward rotation when said dial is released, and means operated by said limited backward rotation for releasing said wheel, for locking said dial against rotation and for hiding said symbols from view during the movement of said wheel.

In witness whereof, I hereunto subscribe my name this 20th day of July, A. D., 1917. 40

OSVALD E. RASMUSSEN.
